Edith Hickling, Minneapolis, Minn.

Application April 29, 1944, Serial No. 113,412

Term of patent 14 years

(Cl. D34—15)

To all whom it may concern:

Be it known that I, Edith Hickling, a citizen of the United States, residing at Minneapolis, in the county of Hennepin and State of Minnesota, have invented a new, original, and ornamental Design for a Combined Toy Locomotive and Tender, of which the following is a specification, reference being had to the accompanying drawing, forming a part thereof.

Figure 1 is a top plan of a combined toy locomotive and tender showing my new design; and Figure 2 is a side elevational view thereof.

I claim:

The ornamental design for a combined toy locomotive and tender, as shown.

EDITH HICKLING.
